UNITED STATES PATENT OFFICE

WILLIAM H. KITTO, OF CANTON, OHIO, ASSIGNOR TO THE HOOVER COMPANY, OF
NORTH CANTON, OHIO, A CORPORATION OF OHIO

SUCTION CLEANER

Application filed May 5, 1930. Serial No. 449,778.

The present invention relates to suction cleaners and particularly to that type of a suction cleaner in which the driving motor for the suction-creating fan is positioned within, and entirely enclosed by, a main casing which defines the exhaust outlet from the fan chamber and to which the dirt separator is attached. More specifically the invention relates to improvements in means for cooling a suction cleaner motor in that type of suction cleaner in which the motor casing is entirely surrounded by the discharge passageway leading from the fan chamber.

In suction cleaners of the aforementioned type reliance is often had solely upon radiation through the motor casing to the dirt-laden air which passes in the surrounding air passageway for motor cooling but it is the teaching of experience that in the high speed motor used in this type of machine that this radiation is not adequate to maintain a sufficiently cool motor for efficiency and long life and for that reason it is necessary to provide additional means for cooling as by passing cooling air directly through the motor. Use cannot be made of the air which encloses the motor casing and which carries the dirt and other foreign substances which has been removed from the covering under going cleaning as the passage of such air through the motor proper would result in injury thereto such as fouling of the bearings, increased wear of the commutator brushes, and the injury to the commutator itself. In a suction cleaner of the type under consideration the present invention provides means by which cooling air is drawn from outside of the main casing into the motor casing and is exhausted therefrom into the dirt-laden air stream after having passed through the motor to perform its cooling function.

In the drawing in which a preferred embodiment of the present invention is disclosed:

Fig. 1 is a side elevation, with certain parts broken away, of a preferred embodiment of the present invention;

Fig. 2 is an enlarged section of an im-

In the drawing a suction cleaner is disclosed which comprises a body or casing 1 which includes the nozzle proper 2, the fan chamber 3, and an enclosing casing 4, which forms the discharge passageway from the fan chamber 3 which is of the type which discharges rearwardly adjacent its entire periphery. A dirt separator or dust bag 5 is secured to the rear of the enclosing casing 4 by suitable means such as 6 and serves to remove the suspended foreign matter from the cleaning air which is discharged thereinto. A handle 7 is provided which is connected to the casing 4 and fan chamber 3, which provides means by which the cleaner may be manipulated by the operator. A switch 8 is suitably positioned upon the handle 7 and is electrically connected to the source of electrical power which enters through the wire 9 at a convenient place in the rear of handle 7 and is continued and makes electrical contact with the driving motor to be hereinafter described.

Positioned within the casing 4 of the cleaner is a totally enclosed motor which is indicated generally by the reference character 10. Motor 10 comprises a casing 11 which is of the totally enclosed type and which is provided with a bearing 12 in its front wall. A rear bearing 13 is carried by an intermediate partition 14 in casing 11 and supported in the bearings 12 and 13 is the rotatable motor shaft 15 upon which is mounted the armature 16. The stationary field 17 of the motor is suitably mounted within the casing 11 and is connected as is the armature 16, to the electrical leads which come into the casing 11 from the handle 7.

Positioned upon the motor shaft 15 immediately forward of the casing 11 and within the fan chamber 3 is the suction-creating fan 18 which is fixedly mounted upon the shaft 15 and rotates therewith and functions to draw air, in the operation of the machine, through the suction nozzle 2 into the fan chamber 3, and exhaust same into the space between the outer casing 4 and the motor casing 11. The air is forced rearwardly in the air passageway to the end of the motor

100

casing 11, which is stream-lined as indicated at 19, and into the dust bag 5.

The passage of the dirt-laden air from the fan chamber 3 rearwardly along the casing 11 of the motor 10 removes part of the heat generated in the motor operation but it is the means hereinafter described which forms the present invention that insures the cool performance of the motor.

10 A support, of which an enlarged section is shown in Fig. 2, is positioned at the rear of the motor casing and extends between said casing and the enclosing casing 4. This support or bushing comprises a hollow bolt, 15 which is indicated generally by the reference character 20. Bolt 20 is provided with a head 21 and a hollow body portion 22 which extends inwardly through the circular opening 23 provided in the enclosing casing 4. The inner end of body 22 of bolt 20 is threaded as at 23 and seats within a hollow bushing 24 which is internally threaded and which is mounted within the opening 25 in the motor casing 11. Bushing 24 is spaced from the casing wall by three circular sound-deadening rings 26, 27 and 28 made of fibre or similar material which are positioned immediately adjacent the edges 30 of the motor casing wall surrounding the opening 25 to prevent any looseness or noise in the bushing 24. An outer metallic plate 29 is positioned immediately adjacent the outer gasket 28 and is clamped thereagainst as by the speening over of the outer end 30 of the bushing 24. The threaded end 23 of bolt 20 seats in screw-threaded relation within the bushing 24 and serves to draw the motor casing 11 to the enclosing casing 4 and compresses therebetween the sound-deadening bushing 31 which encloses the body portion 22 of the bolt 20. The presence of bushing 31 serves also to provide a support for the motor casing and substantially eliminates noise resulting from vibration. Additional supporting means of any desired type may be employed to securely position the motor 10. The entire supporting construction described is simple and provides an opening for the motor to the clean air outside the enclosing casing 4.

55 In the forward wall of the motor casing 11 immediately in the rear of the suction-creating fan 18 are positioned a plurality of openings, of which one is indicated at 32 in Fig. 1, which connect the interior of motor casing 11 with the fan chamber 3. Positioned upon the back of the main suction-creating fan 18 is an auxiliary fan comprising blades 33, 33 which are suitably secured 60 as by rivets 34. The auxiliary fan serves, in the operation of the machine when the main fan 18 is rotated, to create a negative pressure immediately surrounding the bearings 12 which functions to draw the air from 65 within the motor casing 11 through the open-

ings 32 into the fan chamber 3 from which point it is forced by the auxiliary fan blades 33 to the exterior periphery of the fan 18 where it is carried the length of the motor along in the main air stream into the dirt separator 5.

The air which may be drawn through the motor of the suction cleaner in the manner aforescribed, is determined by the size of the opening in the motor support 20 and the openings 32 in the motor casing at the fan chamber end. The capacity of the auxiliary fan is also an element in the determination of the amount of air which is drawn therethrough and these variables may be so related that sufficient cooling air traverses the motor to maintain the desired temperature therein.

Having clearly set forth and described my invention, I claim:

1. In a suction cleaner a main casing including a nozzle, a fan chamber and a discharge passageway, an enclosed motor including a casing positioned in said discharge passageway and sound-deadening means to support said motor comprising a metallic bushing positioned in the wall of said motor casing and spaced therefrom by sound-deadening material, a metallic bolt extending through said main casing into said bushing in screw threaded relation and serving to draw said casings together and a bushing of sound-deadening material enclosing said bolt and spacing said casings.

2. In a suction cleaner a main casing including a nozzle, a fan chamber and a discharge passageway, a motor casing in said passageway, a hollow support positioning said motor casing in said passageway, said casings having openings communicating with said support, said support and said openings comprising means interiorly connecting the motor casing with the atmosphere surrounding the main casing, the forward wall of said motor casing defining a side of said fan chamber, said wall having an opening therein, a motor in said motor casing having a shaft extended thru another opening in said wall into said fan chamber, a suction-creating fan in said fan chamber mounted on the extended end of said shaft and adapted to draw air thru said nozzle and exhaust it in said discharge passageway, auxiliary fan blades on said fan adjacent said motor casing adapted to draw air from said motor casing thru said first opening in said motor casing wall and exhaust it into said discharge passageway.

3. In a suction cleaner, a main casing including a nozzle, a fan chamber and a discharge passageway, a motor casing positioned in said discharge passageway, a motor in said casing, a hollow support positioning said motor casing in said discharge passageway and interiorly connected to said motor casing and to the atmosphere surrounding said main 125

casing, and means to draw cooling air for said motor from the atmosphere through said support into said motor casing.

Signed at North Canton, in the county of
5 Stark, and State of Ohio, this 30th day of
April, A. D. 1930.

WILLIAM H. KITTO.
